UNITED STATES PATENT OFFICE.

HAL R. STAFFORD, OF PLAINFIELD, NEW JERSEY, ASSIGNOR TO ECONOMY DEVICES CORPORATION, OF NEW YORK, N. Y., A CORPORATION OF NEW YORK.

STEAM-ENGINE VALVE-REVERSING GEAR.

1,165,811.

Specification of Letters Patent. Patented Dec. 28, 1915.

Application filed July 23, 1915. Serial No. 41,455.

To all whom it may concern:

Be it known that I, HAL R. STAFFORD, of Plainfield, in the county of Union and State of New Jersey, have invented a certain new and useful Improvement in Steam-Engine Valve-Reversing Gears, of which improvement the following is a specification.

The object of my invention is to provide a power operated valve reversing mechanism embodying the features of capability of rapid movement in effecting complete reversal of the valve gear, positive locking of the valve gear in desired adjustment, automatic lubrication of the important wearing parts, and removal of all lost motion of the wearing parts.

The improvement claimed is hereinafter fully set forth.

In the accompanying drawings: Figure 1 is a side view, in elevation, of a reversing gear embodying my invention; Fig. 2, a plan or top view; Fig. 2^a, a vertical transverse section, on the line *xx* of Fig. 1; Fig. 3, an axial section, on an enlarged scale, 25 through the rotary nut, showing the traversing screw in elevation, and illustrating the means for simultaneously adjusting the thrust bearings and the fit of the screw; Fig. 4, a rear view, in elevation, of the appliance; Fig. 5, a vertical section through the frame, on the line *yy* of Fig. 1; and Fig. 6, a front view of the frame.

Referring to the drawings, in the practice of my invention, I provide a substantially rectangular supporting frame, 1, which in the case of a locomotive engine, may, as shown, be bolted to the side of the firebox, and upon which are formed upper and lower guides, 1^a. A separable casing, 40 comprising a lower main body, 2, and an upper detachable cap, 2^a, is formed upon or secured to the rear end of the frame, 1, that is to say, the end farther from the valve gear which is to be controlled by the appliance. The lower portion of the main body of the casing is made tight and serves as an oil reservoir, as indicated by the portion which is shown in section in Fig. 1.

A reversible rotary high speed motor, 3, 50 which may be of any suitable and preferred known type, and which, as it does not, in and of itself, form part of my present invention, is not herein illustrated in detail, is mounted in the casing, 2, its casing being 55 prevented from movement relatively to the

main casing, by a spindle, 3^a. The motor is supplied with motive fluid, as steam or compressed air, through a pipe, 4, controlled by a suitable reversing valve which is operated by a handle, 5. When the handle is in middle or neutral position, as shown in the drawings, motive fluid is shut off from the motor, and when moved forward or backward, it is admitted in direction to effect, through the connections to be presently described, adjustment of the valve gear in the corresponding direction.

A spur gear, 6, detachably mounted upon the shaft, 3^b, of the motor, engages a corresponding gear, 7, which is formed integral with, or secured to, the rear section, 8, of a two part main nut, 8, 8^a, journaled in thrust bushings, 9, 9^a, fixed in a bearing, 10, on the frame, and adapted to rotate therein, but held against longitudinal movement. 70 Interlocking clutch projections, 8^b, which are formed on the adjoining ends of the section of the nut, prevent relative rotation of the sections, while permitting relative longitudinal adjustment thereof. The forward section, 8^a, of the nut, is externally threaded, and provided with a spanner adjusting nut, 11, bearing against the outer end of the adjacent bushing, 9^a, and a jam nut, 11^a. The thread of the nut, which is of comparatively coarse pitch, engages a corresponding thread on a longitudinally movable traversing screw, 12, journaled in a bearing, 12^a, in the frame. The forward end of the traversing screw is secured to a cross head, 13, which is fitted to slide between the guides, 1^a, of the frame, and to which the rear end of the reach rod, 14, is pivotally connected, the front end of said rod being coupled to the upper arm of the reverse shaft, (not shown), in the ordinary manner. The traverse of the cross head in either direction is limited by front and rear stops, 15, 15^a, fixed to the frame, and the traversing screw projects, when at the rear terminal of its range of movement, into a socket, 16, fixed to the rear end of the casing, 2.

The traversing screw is locked, when the desired adjustment of the valve gear has been effected, by a locking latch, 17, journaled in the casing, 2, and adapted to engage the gear, 7, the latch being engaged with, and disengaged from, the gear, by a latch handle, 17^a.

Adjustment of the sections, 8, 8^a, of the

nut, to the traversing screw, for the purpose of taking up wear of the screw and nut, is effected, by tightening the adjusting nut, 11, and jam nut, 11^a, thereby forcing the sections of the main nut longitudinally apart, by the reaction of the nut, 11; on the adjacent thrust bushing, 9^a, with the result of causing each section of the main nut to fit closely in one direction only, and the sections to fit the thread of the traversing screw without longitudinal lost motion in either direction. It will be seen that before the sections of the main nut can be forced apart as described, all longitudinal lost motion between the adjusting nut, 5^b, the gear, 7, and the thrust bushings, 9, 9^a, will be taken up, and by the further rotation of the adjusting nut all longitudinal lost motion is eliminated from the parts at a single operation.

In the operation of the appliance, it being assumed that it is desired to move the valve gear into, or forwardly in, forward motion position, the operating handle, 5, of the motor is moved forwardly, or to the right in Figs. 1 and 2, whereby motive fluid is admitted to the motor in direction to cause it to rotate the gears to effect forward movement of the traversing screw and cross head to the desired position. The supply of motive fluid to the motor is then cut off by returning the operating handle to middle position, and the traversing screw is locked by engaging the latch, 17, with the gear, 7. Adjustment in the opposite direction is similarly effected by movement of the operating handle to the left.

I claim as my invention and desire to secure by Letters Patent:

- 40 1. In a valve reversing mechanism, the combination of a rotatable nut, a longitudinally movable traversing screw engaging said nut, bearings on which the thrust of said nut is exerted, and adjustable means for taking up wear between the nut and the bearings and between the nut and screw, in a single operation.
- 45 2. In a valve reversing mechanism, the combination of a main nut, comprising two sections engaged by interlocking clutch projections, a longitudinally movable traversing screw engaging said nut, bearings on which the thrust of the sections of said nut is independently exerted, and an adjusting

nut engaging one of the sections of the nut 55 and abutting against the adjacent thrust bearing.

3. In a valve reversing mechanism, the combination of a rotatable nut, power actuated means for rotating said nut, a longitudinally movable traversing screw engaging said nut and adapted for connection to a valve gear element, bearings on which the thrust of said nut is exerted, and adjustable means for taking up wear between the nut 60 and the bearings and between the nut and screw, in a single operation.

4. In a valve reversing mechanism, the combination of a supporting frame, two parallel guides thereon, a casing fixed to the 70 frame, a reversible rotary motor mounted in the casing, a longitudinally movable traversing screw journaled in the frame, a nut engaging said screw adjacent to one end of the guides and rotatable by gearing from the 75 motor shaft, and a cross head fixed to the end of the traversing screw farther from the nut and working between the frame guides.

5. In a valve reversing mechanism, the 80 combination of a supporting frame, guides thereon, a separable casing fixed to the frame and having an oil reservoir formed in its base, a reversible rotary motor mounted in the casing, a longitudinally movable traversing screw journaled in the frame, a nut 85 engaging said screw, gearing through which the nut is rotated by the motor and which receives lubrication from the oil reservoir, and a cross head fixed to the traversing 90 screw and working on the frame guides.

6. In a valve reversing mechanism, the combination of a supporting frame, guides thereon, a casing fixed to the frame, a reversible rotary motor mounted in the casing, a longitudinally movable traversing screw journaled in the frame, a nut engaging said screw, gearing through which the nut is rotated by the motor, a locking latch journaled on the casing and adapted to engage 95 a member of the gearing, and a cross head fixed to the traversing screw and working on the frame guides.
